COMBINED CAN OPENER AND CLOSURE

Loran L. Laughlin, 2541 Maywood Drive,
Salt Lake City, Utah 84109

Filed June 11, 1970, Ser. No. 23,440

Term of patent 14 years

Int. Cl. D8—02

U.S. Cl. D8—34

FIG. 2

FIG. 1

FIG. 3

FIG. 4

FIG. 5

FIG. 1 is a side view in elevation of the combined can opener and closure showing my new design;

FIG. 2 is a front elevational view thereof;

FIG. 3 is a rear elevational view thereof;

FIG. 4 is a top plan view thereof; and

FIG. 5 is a bottom view thereof.

I claim:

The ornamental design for a combined can opener and closure, as shown.
